UNITED STATES PATENT OFFICE.

JAMES R. COVE, OF ARLINGTON HEIGHTS, MASSACHUSETTS, ASSIGNOR TO LEVER BROTHERS COMPANY, OF CAMBRIDGE, MASSACHUSETTS, A CORPORATION OF MAINE.

METHOD OF AND APPARATUS FOR CUTTING SOAP AND THE LIKE.

Application filed October 30, 1922. Serial No. 597,711.

To all whom it may concern:

Be it known that I, JAMES R. COVE, a citizen of the United States, residing in Arlington Heights, in the county of Middlesex, in the State of Massachusetts, have invented certain new and useful Improvements in Methods of and Apparatus for Cutting Soap and the like, of which the following is a specification.

10 The invention relates to a method of and apparatus for cutting soap and the like into pieces or flakes of uniform size and regular shape.

Flake soap is commonly sold in cartons. 15 The filling and weighing of the cartons is usually performed by automatic machinery. Considerable difficulty has heretofore been experienced in depositing the requisite quantity of soap flakes in each carton. It 20 frequently happens that a carton receives more or less than the specified amount of soap flakes, with consequent loss to the manufacturer or to the consumer. This situation has been attributed to the fact that the flakes 25 have heretofore been and now commonly are of irregular shape and varying sizes. This has made it difficult to control the stream of soap flakes passing into the cartons from the hoppers of the filling and weighing 30 machines. The object of the invention is to avoid this difficulty by producing a method of and apparatus for cutting the soap into pieces or flakes of uniform size and regular shape. The exact contour of 35 the shape is of less importance, the desideratum being that the flakes be of a given and uniform size. By the form of apparatus chosen to carry out the method of the invention the sheet of soap is 40 cut into diamond shaped pieces or flakes. It will be understood, however, that the invention is not to be restricted to the production of diamond shaped flakes of soap or the like, inasmuch as flakes of various other shapes 45 may be equally well produced by the practice of the invention. The method and apparatus of the invention are fully described hereinafter and particularly pointed out in the appended claims.

50 In the accompanying drawings the preferred form of apparatus for carrying out the method part of the invention is illustrated as applied to the finishing roll of a soap machine. Fig. 1 is a top plan, with

parts broken away, of the discharge end of a 55 soap machine of common construction, showing the apparatus of the invention applied to the finishing roll; Fig. 2 is an end elevation, partly in section, of the parts shown in Fig. 1; Fig. 3 is a rear end elevation of one 60 of the cutters (and its support) for cutting the sheet of soap into longitudinal strips; Fig. 4 is a side elevation, partly in section, of the parts shown in Fig. 3; Fig. 5 is a 65 front elevation of one of the units of the cutter for cutting the sheet of soap into transverse strips; Fig. 6 is a plan of a portion of the sheet of soap, showing diagrammatically the preferred method of cutting 70 to produce flakes of uniform size and regular 75 shape; and Fig. 7 is a perspective view of one of the diamond shaped flakes.

The method of the invention consists in forming a plurality of series of uniformly spaced and intersecting cuts in the sheet of 80 soap as it passes over the finishing roll of the soap machine. The invention is conveniently practiced by forming a series of uniformly spaced transverse cuts (preferably diagonal) in the sheet of soap and then 85 forming a series of uniformly spaced longitudinal cuts intersecting the transverse cuts. If the transverse cuts are at right angles with the longitudinal cuts, it will be obvious that the resulting pieces or flakes will be 90 square and that if the transverse cuts cross the longitudinal cuts diagonally, the resulting pieces or flakes will have a diamond shape. By variously arranging the relationship of the cutting edges, pieces or flakes 95 of other contour may be produced.

The invention may be practiced in connection with any usual or preferred form of soap machine having a finishing roll over which a sheet of soap is adapted to travel. 100 The discharge end of such a machine is shown in the drawings. The finishing roll 10 is shown as mounted in the two side frames 11 and may be driven from any convenient source of power. The finishing roll 10 travels in the direction indicated by the arrow in Fig. 2 and the sheet of soap of necessity travels in the same direction. When the sheet of soap has been cut, it is removed from the finishing roll 10 by a scraper 12 arranged axially of the roll and bearing against the surface of the roll. The parts 105 thus far described and their associated parts

are all of common and well known construction and therefore need no further particular description.

The preferred form of apparatus for carrying out the method part of the invention comprises a cutter 14 arranged axially of the finishing roll 10 and having a series of spirally disposed, uniformly spaced cutting edges. The cutter 14 is journaled in brackets 15 loosely mounted on the rod 16 which extends transversely across the top of the machine and is secured to the frames 11. The cutter 14 rests on the surface of the finishing roll 10 and the rotation of the latter causes the cutter to rotate. The cutter 14 consists of a series of cutter units 17, as shown in Fig. 5. The cutter units 17 are provided with key-ways 18 adapted to receive a key 19 fixed in a spline cut axially in the surface of the shaft 20 on which the cutter 14 is mounted. The key-ways 18 are so positioned with respect to the cutting edges 21 of each cutter unit that when the cutter units are assembled, the cutting edges 21 will form continuous spirals throughout the length of the cutter 14. Hence, when a sheet of soap travels over the surface of the finishing roll 10 and under the cutter 14 a series of oblique, uniformly spaced cuts will be formed transversely of the sheet of soap, as indicated by the dot and dash lines 23 in Fig. 6. The sheet of soap is conveniently about six thousandths of an inch in thickness.

Although the cutter 14 is heavy and is mounted to rest upon the periphery of the finishing roll, the transverse cuts made in the sheet of soap by the cutter do not sever it into detached strips. The transverse strips formed by the cutter 14 adhere together at the bottom of the cuts by a very thin web, so that they are properly presented to the cutters which form the intersecting or longitudinal cuts in the sheet of soap. The longitudinal or intersecting cuts are formed by a series of uniformly spaced cutter discs 25, each of which is mounted in a separate bracket 26 provided with a hook-shaped head 27. To eliminate friction, the cutters 25 are mounted on ball bearings 28. The series of cutters 25 are mounted to rest upon the periphery of the finishing roll, and for this purpose the hook-shaped ends 27 of the brackets 26 loosely engage the rod 29 supported longitudinally of the finishing roll from extensions 30 of the brackets 15. The brackets 26 are machined to a uniform thickness so that when the cutters 25 are assembled, as shown in Fig. 1, the cutters 25 are spaced a uniform distance apart, preferably about one-half inch. The distance between the cutting edges 21 of cutter 14 is also conveniently about one-half inch. As the sheet of soap advances between the finishing roll and the series of cutters 25, a series of uniformly spaced longi-

tudinal cuts 31 are formed in the sheet of soap, intersecting the transverse cuts 23. These longitudinal cuts 31 also do not sever the soap into separate strips. The webs which hold the sheet of soap together after both cutting operations have been performed are, however, so thin that when the scraper 12 removes the cut end of the sheet of soap from the finishing roll, the soap breaks up into diamond shaped flakes 32, one of which is shown in Fig. 7.

One practical result of cutting the sheet of soap into pieces or flakes of uniform size and regular shape is that the automatic filling and weighing machines can operate more efficiently and at a higher rate of production. Moreover, the quantity and weight of the flakes placed in each carton is more uniform than has been possible with the old methods of flaking the soap. So far as known, this is the first time it has been proposed to cut soap into flakes of uniform size and shape and therefore it is desired to claim the invention broadly.

Having thus described the invention what is claimed as new is:—

1. The method of producing flaked material which consists in feeding a relatively thin sheet of the material to be flaked in one direction, cutting said sheet in a transverse direction to the line of feed, said cutting operation terminating short of complete penetration, then cutting said sheet in a direction substantially parallel to the line of feed, said second named cutting operation terminating short of complete penetration, and finally separating the sheet into flakes along the line of the cuts.

2. The method of cutting a sheet of soap and the like into flakes which consists in feeding the sheet in one direction and forming a series of oblique cuts transversely of the line of feed, which cuts do not sever adjacent portions of the sheet, then forming a series of cuts adapted to intersect said oblique cuts, and finally separating the sheet into flakes along the lines of the cuts.

3. The method of cutting a sheet of soap and the like into flakes of uniform size and shape which consists in feeding the sheet in one direction and in forming a series of uniformly spaced cuts adapted to partially separate adjacent portions of the sheet and extend transversely thereof in one direction, forming a series of uniformly spaced cuts in another direction which intersect said first named cuts, and finally deflecting said cut sheet during a continuation of the feeding operation, which deflection serves to separate the sheet into flakes along the lines of the cuts.

4. An apparatus for cutting soap and the like into diamond shaped flakes comprising a moving surface over which the material to be cut is fed, a cutter having a series of

equally spaced spiral cutting edges formed thereon adapted to rest upon the moving surface and to be actuated thereby, and a series of spaced cutters for cutting the material into longitudinal strips.

5. An apparatus for cutting a sheet of soap and the like into diamond shaped flakes comprising a cutter having a series of spiral cutting edges for forming obliquely disposed cuts in the sheet of the material, a series of spaced cutters for forming a series of longitudinal cuts in the material and which intersect the oblique cuts, and means for effecting relative movement between the cutters and the sheet of material.

6. An apparatus for cutting a sheet of soap and the like into regularly shaped pieces of uniform size, comprising a moving roll over which the sheet of soap is fed, a cutter arranged axially of the roll and having a series of uniformly spaced cutting edges adapted to rest on the surface of the roll so as to thereby rotate the cutter and form a series of transverse cuts in the sheet

of soap, a series of uniformly spaced cutting edges arranged beyond the first cutter for forming a series of cuts in the sheet of soap which intersect the transverse series of cuts, and means for removing the cut flakes from the roll.

7. An apparatus for cutting soap and the like into regularly shaped flakes of uniform size comprising a moving surface over which the material to be cut is fed, a cutter arranged transversely of the direction of travel of the moving surface and having a series of equally spaced cutting edges formed thereon adapted to rest upon the moving surface so as to be actuated thereby to form in the sheet of material a series of uniformly spaced transverse cuts, a series of uniformly spaced cutting edges adapted to contact with the moving surface at a point beyond the first cutter to form in the sheet of material a series of uniformly spaced cuts which intersect the transverse cuts, and means for removing the cut flakes from the surface.

JAMES R. COVE.
